SETTING FRAME

Ernest T. Phoenix, Amsterdam, N. Y., assignor to
Bigelow-Sanford Carpet Co. Inc., Thompson-
ville, Conn., a corporation of Massachusetts

Application February 23, 1934, Serial No. 712,519

9 Claims. (Cl. 28—55.5)

This invention relates to the manufacture of pile carpets and rugs and is more particularly directed to a setting frame or machine for winding a series of yarns side by side on a receiver or spool.

In accordance with the present practice in winding a series of yarns on a receiver or spool by a setting machine or frame, a presser roll is ordinarily employed to act upon the receiver or spool and the yarn as it is wound thereon, and the pressure of the roll upon the yarn is regulated by weights and levers, or by springs connected to a sliding member which supports the presser roll. The compactness of the yarn upon the receiver or spool depends, of course, on the pressure exerted by the presser roll. The pressure on the presser roll is required to be regulated and changed from time to time to suit the varying conditions that arise in use, and when the required amount of yarn has been wound on the receiver or spool it is necessary to disengage the presser roll from the yarn on the receiver or spool and the operator has been required to lift the presser roll by hand the required distance to remove the presser roll from the yarn on the receiver or spool, and to further provide a clearance over the yarn in order to swing the presser roll forwardly to permit removal of the wound receiver or spool. Also, when it is required to insert or engage an empty spool with its operating means, when the presser roll is down in working position, the operator must again lift the presser roll by hand the full distance of the vertical lift.

One of the objects of the present invention is to provide means for the elimination of the labor fatigue of the operator in lifting the top roll, as described, and further to provide means for exerting a more uniform and consistent pressure of the presser roll on the winding yarn than heretofore, which uniform pressure insures a more evenly wound receiver or spool of uniform compactness or density. A further object of the invention is to provide means for perfecting the winding of the yarn receivers or spools in an Axminster setting machine or frame, to insure more perfect fabric during the weaving operation.

More specifically stated the present invention provides fluid pressure means for exerting a uniform pressure of the presser roll upon the yarn and for finally lifting the presser roll from the yarn when a full receiver has been accomplished that the presser roll may be swung away from the wound receiver and permit its removal from the machine.

The invention and novel features thereof will

best be made clear from the following description and accompanying drawing of one good form thereof.

The drawing presents a side elevation of a setting machine or frame embodying the present invention.

The frame 1 of the machine may be of any usual type for the support of the operating parts, and mounted for rotative movement on the machine frame are the operating rollers 2 and 3 for 10 rotating the yarn receiver or spool. The operating rollers 2 and 3 may be conveniently driven from the main driving shaft 4 but the driving connection between the driving shaft and operating rollers is not herein shown because it forms 15 no essential part of the present invention.

Mounted in suitable guides 5 is a presser roll supporting member constituted in the present instance as a slide 6 which at its upper end at 7 supports the presser roll 8 and in order that the 20 presser roll may be swung to one side to permit the wound receiver or spool to be removed from the machine the upper portion 7 of the presser roll supporting means is pivoted at 9 to the slide 6.

When the parts thus far described are in their 25 operative relation the receiver or spool 10 rests upon the operating rolls 2 and 3 while the presser roll 8, as will more fully appear, presses upon the yarn receiver or spool and the yarn load as it gradually increases in amount.

Associated with the parts thus far described is a cylinder 11, shown in the present instance as located at the lower part of the machine frame, and operating in the cylinder 11 is a piston 12, and extending transversely of the machine or 35 setting frame is a shaft 13 having an arm 14 affixed thereto at each side of the machine.

Connected to each of the arms 14, one at each side of the machine, is a connecting rod 15 which at its upper end is joined at 16 to an adjustable 40 member 17 supported by a stud 18 secured to the presser roll supporting means, the construction being such that upon movement of the arms clockwise or contra-clockwise, the presser roll supporting means will have movements imparted 45 thereto either in a downward or an upward direction.

Secured to the transverse shaft 13 is an arm 19 having a slotted end portion 20 which is engaged at 21 with the piston rod 22, whereby 50 movement of the piston and piston rod will be imparted to the transverse shaft 13 and through the arms 14, hereinbefore described, such movements will be imparted to the presser roll 8.

In accordance with the present invention the 55

presser roll is to be given its desired movements through fluid pressure in the cylinder 11.

5 Mounted at a convenient position on the machine frame is a controlling valve 23 for controlling the fluid pressure as it comes from the source of supply through the pipe 24, and connected with the valve is the conduit or pipe 25 which communicates at 26 with the fluid pressure reduction valve 27 which may be of any of the usual forms of such valves.

10 Connected to the lower portion of the fluid pressure reduction valve is a pipe or conduit 28 which has the downwardly extending portion 29 connected to the cylinder 11 above the piston 12, the construction being such that when the control valve 23 is set for the ingress of fluid pressure to and through the reduction valve 27, such pressure will be exerted above the piston 12 and therefore exert a downward pressure of the presser roll 8 upon the yarn on the receiver being wound.

15 Communicating with the controlling valve 23 is a conduit or pipe 30 which extends downwardly and communicates at 31 with the lower portion of the cylinder 11 below the piston 12, and in order that the flow of fluid pressure to and through the reduction valve 27 or to and through the pipe or conduit 30 may be controlled, the controlling valve 23 is provided with a manually operated handle or means 32.

20 Associated with the controlling valve 23 is an exhaust port 33 which, when the handle 32 of the controlling valve is in the full line position, as shown, will communicate with the outside atmosphere and permit pressure in the pipe or conduit 30 to exhaust. When, however, the handle 32 is moved to the dotted line position, as indicated, the exhaust port is closed and fluid pressure from the source of supply will pass through the pipe 30 to the lower part of the cylinder below the piston 12.

25 Connected to the upper portion of the cylinder 11 is a relief valve 34 of usual construction, and connected to the lower portion of the cylinder below the piston is another relief valve 35.

30 Assume that the yarn receiver or spool 10 is in position for winding, as shown, and in contact with the operating rollers 2 and 3 and the presser roll 8, and that the series of yarns a to be wound upon the receiver or spool are presented, as usual, the piston 12 in the cylinder 11 will be at its lowest position, as shown, and the operating lever or handle 32 will be in the position shown by full lines in the drawing, with the result that fluid pressure will pass through the controlling valve 23 to the pressure reduction valve 27 and be admitted to the top portion of the cylinder 11 above the piston, so that as the load of yarn upon the receiver or spool progresses and the 35 yarn load increases in size the piston will be drawn upwardly by the presser roll against the fluid pressure admitted to the top of the cylinder. At this time the exhaust port 33 will be open to the atmosphere to permit the piston to rise under the dictates of the presser roll against the fluid pressure.

35 When the required amount of yarn or yardage has been wound on the receiver or spool 4, the setting frame automatically stops under the action of any of the usual automatically acting stop devices. The operator then moves the lever 32 from its full to its dotted line position, as shown. This change in the controlling valve changes and diverts the direction of fluid pressure from the source of supply through the oper-

40 ating valve into and through the pipe 30 to the bottom of the cylinder below the piston. This pressure, not being reduced, as was the pressure on top of the piston, forces the piston upwardly against the compression of a valve 34. As the piston continues to rise, the roller 8 also rises and when the presser roll 8 is raised away from the yarn on the receiver or spool to its highest position, as shown at x, the operator swings the presser roll to a position shown at y at which time the full receiver or spool may be disengaged and the next receiver or spool to be wound may be placed in contact with the operating rolls 2 and 3, whereupon the presser roll 8 is 45 swung back into its initial position x.

45 With the empty spool in contact with the operating rollers 2 and 3 and presser roll 8 in position at x the operator swings the handle 32 operating the valve 23 from the dotted to the full line position which reverses the air pressure to 50 the top of the piston and the presser roll is thereupon forced to its initial starting position, as indicated by full lines in the drawing.

55 As the piston is forced downwardly the action is against the compression set up by predetermined pressure in the relief valve 35, but at this point it is to be noted that the operating valve 23 connects the exhaust port 33 with the pipe 30. When the handle 32 of the controlling valve 23 is in position shown by full lines, the exhaust 55 port 33 is open thereby preventing a vacuum under the piston when the piston is rising in the cylinder 11, and also when the piston is in its up position and the handle of the controlling valve is put in its full line position and the air 60 pressure is directed upon the top of the piston, the exhaust port being open forms an escape for the compression in the bottom of the cylinder. This is necessary because the relief valve 35 would necessarily be set to a higher pressure than 65 enters on top of the piston through the fluid pressure reduction valve 27. When the handle 32 of the controlling valve is in dotted line position the exhaust port 33 is closed thereby allowing an initial pressure from the source of supply 70 to pass into the pipe 30 for raising the presser roll, as previously noted.

75 The compression at the end of the piston stroke forms a cushion or shock absorber. Concisely stated, the pressure of the presser roll 8 on the 75 yarn load is produced by air pressure instead of by springs or weights, as now used, and the control of raising or lowering the presser roll 8 is at the disposition of the operator by the manipulation of the valve handle 32, so that all manual fatigue in manipulating the presser rolls is eliminated.

What is claimed is:—

1. In a setting frame for winding a series of 80 yarns side by side on a receiver, the combination of means for rotating the receiver, a presser roll, means for supporting the presser roll for movement towards and from the receiver, a source of fluid pressure, and connections between the 85 source of fluid pressure and the presser roll supporting means including a fluid pressure reduction valve for controlling the fluid pressure exerted on the presser roll.

2. In a setting frame for winding a series of 90 yarns side by side upon a receiver, the combination of means for rotating the receiver, a presser roll mounted for movements into and from engagement with the yarn on the receiver, and fluid pressure actuated means connected to 95

the presser roll for effecting such movements of the presser roll.

3. In a setting frame for winding a series of yarns side by side upon a receiver, the combination of means for rotating the receiver, a presser roll mounted for movements into and from engagement with the yarn on the receiver, and fluid pressure actuated means for effecting such movements of the presser roll and a valve for determining which of said movements shall be effected by the fluid pressure actuated means.

4. In a setting frame for winding a series of yarns side by side upon a receiver, the combination of means for rotating the receiver, a presser roll, fluid pressure actuated means including a cylinder and piston for moving the presser roll into engagement with the receiver and the yarns wound thereon and exerting a substantially uniform pressure on the yarn during the winding operation.

5. In a setting frame for winding a series of yarn side by side upon a receiver, the combination of means for rotating the receiver, a presser roll, fluid pressure actuated means for moving the presser roll into engagement with the receiver and the yarn wound thereon and exerting a substantially uniform pressure on the yarn during the winding operation and means for reversing the operation of the fluid pressure actuated means to remove the presser roll from engagement with the yarn on the receiver.

6. In a machine of the character described, the combination of a receiver and means for rotating it to wind yarn thereon, a presser roll movable towards and from the receiver, a cylinder and piston one of which is connected to the presser roll, means for introducing fluid pressure into the cylinder at one side of the piston to move the presser roll into pressure contact with the yarn on the receiver, and means for introduc-

ing fluid pressure into the cylinder at the other side of the piston to move the presser roll out of contact with the yarn on the receiver.

7. In a machine of the character described, the combination of a receiver and means for rotating it to wind yarn thereon, a presser roll mounted for movements towards and from the receiver, a piston and cylinder one of which is connected to the presser roll, a source of fluid pressure connected to the cylinder, a valve mechanism operable to admit fluid pressure into the cylinder at one side of the piston to cause the presser roll to exert pressure upon the yarn on the receiver and operable to admit fluid pressure into the cylinder at the other side of the piston to move the presser roll away from the yarn on the receiver.

8. In a setting frame for winding a series of yarns side by side on a receiver, the combination of means for rotating the receiver, a presser roll, a cylinder, a piston in the cylinder and connected to the presser roll, a source of fluid pressure, and means for introducing fluid pressure into the cylinder at one side of the piston to move the connected presser roll towards the receiver and exert a substantially uniform pressure upon the yarn on the receiver during the winding operation.

9. In a setting frame for winding a series of yarns side by side upon a receiver, the combination of means for rotating the receiver, a presser roll mounted for movements into and from engagement with the yarn on the receiver and exerting pressure on the yarn as it is wound on the receiver, and fluid pressure actuated means connected to the presser roll for lifting the latter away from contact with the yarn on the receiver, and a valve for controlling the fluid pressure.
